UNITED STATES PATENT OFFICE.

WILLIAM C. HELLER, OF MONTPELIER, OHIO.

MERCHANDISE-CABINET.

1,116,817.

Specification of Letters Patent. Patented Nov. 10, 1914.

Application filed April 15, 1913. Serial No. 761,394.

To all whom it may concern:

Be it known that I, WILLIAM C. HELLER, a citizen of the United States, residing at Montpelier, in the county of Williams and 5 State of Ohio, have invented certain new and useful Improvements in Merchandise-Cabinets, of which the following is a specification.

This invention relates to an improvement 10 in merchandise cabinets.

The primary object of the invention is to provide a cabinet disposed to contain various articles of merchandise with a closure which may be brought to assume a position immediately in front of the cabinet, the closure forming a support for samples of 15 the articles arranged within the cabinet.

A further object of the invention is to provide a supporting means for the closure, 20 whereby it may be normally swung to assume a position immediately in front of the goods containing compartments which constitute the cabinet and form an effectual closure for the cabinet, and which, when it 25 is desired to remove goods from the cabinet, may be moved to a point to one side of the same in order that it will not interfere with the removal of the goods.

For a full understanding of the invention, 30 reference is to be had to the following description and accompanying drawings, in which:—

Figure 1 is a front elevation of a portion of a store cabinet, one of the closures being 35 shown as open to afford access to a section of the cabinet; and Fig. 2 is a perspective view of the hinge member which supports the closure.

Corresponding and like parts are referred 40 to in the following description and indicated in all the views of the accompanying drawings by the same reference characters.

In the drawings, 10 designates a cabinet which consists of the frame 11 and the supporting shelves 12. Those shelves are spaced 45 from the outer edge of the frame, the longitudinal members 13 and the vertical members 14 of the frame being beveled as at 15. Drawers or trays 16 are arranged on the 50 shelves and are disposed to contain merchandise. A door or closure 17 is received within the frame, there being a number of such doors or closures supported by the cabinet consistent with the number of sections 55 of the cabinet, the sections being divided by the vertical members 14.

The doors 17 consist of the panels 18, to the vertical edges of which are secured battens 19 and to the longitudinal edges of which battens 20 are secured. These battens 60 are disposed at an angle to the panel in order that, when the door is brought into contact with the frame, they may be snugly received by the beveled members 13 and 14 of the frame. A frame 21 for the glass panel 21' is secured to the battens 19 and 20, said frame consisting of the vertically extending members 22 and the horizontal members 23. This frame, when the door is closed, is disposed flush with the outer face 65 of the vertically and horizontally extending portions of the frame of the cabinet. 70

A bracket 24 is supported at the base and at a point adjacent the top of each of the vertically extending members 14 of the 75 frame. This bracket consists of the bar 25, which is bolted to the members 14, and the right angle extensions 26, the extensions 26 extending within the frame of the cabinet and being secured thereto. It will be noted 80 that while these members may extend within recesses formed in the cabinet, they may embrace the top and bottom of the cabinet and be fastened thereto by means of screws. Each of the brackets is formed with a plurality of pintle lugs 27 which receive a rod 28. This rod extends the entire height of 85 the cabinet, terminating flush with the ends of the outermost pintle lugs 27 which are a continuation of the extensions 26. 90

A hinge member 29 is supported by each of the brackets 24. This member consists of the arm 30 formed with a pintle lug 31 which is of a length slightly less than the distance between the pintle lugs 27 of the 95 bracket members. The pintle lug 31 receives the rod 28, being disposed between the pintle lugs of the bracket and secured to the rod by set-screws 30'. The arms 30 taper toward their outer terminals 32 and are provided with apertured lugs 33. The arms of the two hinge members are spaced from each other to a greater distance than the height of the door 17, the arms being of a length slightly greater than one-half the width of 100 the door. 105

A bracket 34 is supported by the upper and lower longitudinal members of the frame 21, the brackets 34 being formed with pintle lugs 35 which receive a pin 36 carried by the lug 33 of the arm 30. These 110 extensions may either be formed integral

with the lug 33 or a pin may be inserted through the lugs and locked against displacement. It will be noted by this construction that the door 17 is rotatably supported between the lugs 33 of the arms 30, and is capable of being swung to a position where it may form a closure for the adjacent cabinet section.

The many advantages of a construction of this character will be clearly apparent, as it will be noted that the door may be readily brought to a position where the frame, which is supported by the batten strips, may be disposed flush with the outer faces of the horizontal and vertical members of the cabinet frame. It will also be seen that when it is desired to remove merchandise from the container 16, the closure may be moved outwardly from the cabinet and then rotated to assume a position where it will not interfere with the withdrawal of the containers, the goods which are supported on the panel 17 being disposed where they may be viewed by the customer.

Particular attention is called to the formation of the door 17, and to the fact that the outer face of the panel may form a supporting rack for merchandise, displaying, when closed, samples of the merchandise contained

within the cabinet. It will be obvious that the samples, while exposed to view, are set back sufficiently within the cabinet to prevent their accidental displacement. It will also be seen that the entire structure is such as may be easily and economically manufactured, and that the various parts may be readily assembled.

What I claim is:

In a merchandise cabinet having a plurality of separate compartments, a pair of vertically spaced brackets hinged to the cabinet adjacent each compartment, a closure for each compartment, each of said closures consisting of an open faced casing adapted, when in closed position, to display samples of the goods held within the cabinet, each of said closure members being rotatably mounted in a pair of bracket members whereby the closure of each compartment may be swung into open position and disposed with its rear face superposed on the closure of the next adjacent compartment.

In testimony whereof I affix my signature in presence of two witnesses.

WILLIAM C. HELLER. [L. S.]
